BRIDLE BIT

Harvey A. De Wolfe, Costa Mesa, Calif.

Application August 13, 1945, Serial No. 610,511

3 Claims. (Cl. 54—6)

1

My invention relates to saddlery, with particular reference to bridles, and is directed to an improved form of bridle bit.

My object in the design of these bits is to have more effective and humane control of the horse—a bit that will prevent the horse from throwing the head and chomping the bit. With many of our finest horses, with the ordinary bits, the circulation is shut off, and pressure placed on nerves, until the horse loses all feeling in the lower jaw and that causes what is known as "cold jaw." With my bits, there is no cold jaw, but even coordinated movement and a well arched neck because the bit is conducive to collectiveness.

Referring by numerals and letters to the accompanying drawings, particularly to the construction illustrated in Figs. 1, 2, 3 and 4 inclusive:

Fig. 1 is a side elevation of the basic form of construction with adjacent portions of a bridle in which it is to be incorporated;

Fig. 2 is front elevation with parts in section;

Fig. 3 is a back view of the shaft bit with the center section removed and with the center arched member connecting the shafts;

Fig. 4 is a cross section of the center arched member and the inside end of the shaft bit, indicating the tilt forward of the center arched member.

In this bit the tilt of center arched member is about twenty-seven degrees, but the tilt may be used as seems best. This center arched member may be changed to include other features.

On the bridle bit shown in Figs. 1 and 2, 30 designates the side plate and lever arm as one member, 11 the rocker arm, 13 the bar bit having its center cut out as designated by A, Fig. 2. The two parts 13—13 of the shaft are connected by an arched member.

This center arched member is arched forward and back as indicated by B—C and B—F Fig. 2, and D—C and D—F Fig. 3. H is the oval outside surface that goes against the roof of the horse's mouth; Fig. 2 E shows the oval inside surface of center arched member that the tongue rests against, Figs. 3 and 4. O is the opening where the tongue of the horse will be protected. (See Figs. 2 and 3.)

Each of the side plates and lever arms 30 provides an aperture 31 at the upper end for headstall 14, and aperture 32 on the back side for curb strap 16 that crosses under the lower jaw of the horse. The side plates and lever arms extend down for aperture 33 for reins 17. For-

2

ward of aperture 32 on the side plates and lever arms, the rocker arms 11 are pivotally mounted on bolt 28 in hole 27 and pass through bushing 34 that is in hole 35 in the side plates and lever arms 30. Nose band 15 with fastenings 21 is attached to upper end of rocker arms 11. On the lower end of rocker arms 11 bar bit 13—13 is rigidly fastened by key 25 and cap 26.

The action is as follows: A pull on reins 17 in aperture 33 in side plates and lever arms 30 rotates the sideplates and lever arms putting pressure on curb strap 16 in aperture 32 and causes a forward movement of head stall 14 in aperture 31, bringing pressure on spacer bearing 34 in hole 35 in side plates and lever arms 30 and hence on bolt 28 which passes through spacer bearing 34 and is fastened in hole 27 of rocker arms 11.

The pressure is divided between the nose band 15 fastened to upper end of rocker arms 11 by fastenings 21 and bar bit 13 with the center arched member which is fastened securely by key 25 and cap 26 to the lower end of rocker arms 11. Thus the pressure on nose band 15 and bar bit 13 with the center arched member is equal to the pressure on the curb strap 16 in aperture 32, a straight forward and back pull.

For the purpose of disclosure and to illustrate the principles involved, I have described the preferred form of my invention in specific detail. The disclosure will suggest to those skilled in the art various changes and modifications that do not depart from the spirit of my concept. I specifically reserve the right to all such changes and modifications that properly come within the scope of my appended claims.

I claim as my invention:

1. In a bit, two aligned members connected by a central arched member, combined side plates and lever arms, and rocker arms pivotally carried by said combined side plates and lever arms, each face of the arched member being forwardly and rearwardly arcuate whereby to insure smooth action and said arched member having an oval, tilted, top portion to engage the roof of the mouth of a horse, the space between the ends of the aligned members and below the arched member protecting the tongue of the horse, the outer ends of the aligned members being fixed to the lower part of each of said rocker arms, the upper and forward end of each of the rocker arms carrying a nose band that crosses the nose of a horse above the nostrils, each of said combined side plates and lever arms having an upwardly extending, apertured portion for connection with

a bridle head stall, a rearwardly extending, apertured portion for the connection of a curb strap that crosses under the lower jaw of a horse, and a downwardly extending, apertured portion to receive the bridle reins.

2. In a bit, a side plate and lever arm, said side plate and lever arm having an aperture at the top for a headstall of a bridle and having a lower, rearwardly extending aperture for a curb strap that passes under the jaw of a horse, said side plate and lever arm extending downwardly and having an aperture for reins at the lower end, and a rocker arm pivotally secured to said side plate and lever arm, the upper and forward end of the rocker arm being adapted to carry a nose band that crosses the nose of a horse above the nostrils, said rocker arm also having a mouth-piece receiving portion on the lower end.

3. In a bit, a mouthpiece comprising two aligned members connected by a central arched member, each face of the arched member being

forwardly and rearwardly arcuate whereby to insure smooth action and said arched member having an oval, tilted, top portion to engage the roof of the mouth of a horse, the space between the ends of the aligned members and below the arch member protecting the tongue.
